UNITED STATES PATENT OFFICE.

EDWIN S. CLARK, OF WALLA WALLA, WASHINGTON.

PROFILE-MAP MACHINE.

1,379,528.

Specification of Letters Patent. Patented May 24, 1921.

Application filed February 15, 1919. Serial No. 277,149.

To all whom it may concern:

Be it known that I, EDWIN S. CLARK, a citizen of the United States, and a resident of Walla Walla, in the county of Walla Walla and State of Washington, have invented a new and Improved Profile-Map Machine, of which the following is a full, clear, and exact description.

The present invention relates to road-map making instruments. An object of the invention is to provide an improved machine to produce automatically a delineation on a record sheet of the profile of the road traversed by the vehicle on which the device is carried.

The nature and objects of the invention will appear more fully upon examination of the following specification and the accompanying drawings forming a part thereof.

In the drawings, in which is shown an illustrative embodiment of the invention,

Figure 1 is a side view of a profile-record-
ing device embodying the invention;

Fig. 2 is a top plan view of the same;
Fig. 3 is a front view of the device;

Fig. 4 is a sectional view showing the reversing gears of the main driving mechanism and the gear shifter therefor, taken on the line 4—4, Fig. 5, looking in the direction of the arrow;

Fig. 5 is a side view of the gear-shifting mechanism shown in Fig. 4;

Fig. 6 is a detail sectional view showing the belt tightener of the record-spool driving mechanism, taken on the line 6—6, Figs. 3 and 7, looking in the direction of the arrow;

Fig. 7 is a sectional view taken on the line 7—7, Fig. 6, looking in the direction of the arrow;

Fig. 8 is a sectional detail view showing the profile tracer together with the operating screws therefor;

Fig. 9 is a sectional view taken on the line 9—9, Fig. 3, looking in the direction of the arrow, of the record-carrying drum and the profile-tracer driving mechanism;

Fig. 10 is a sectional view showing the record-strip, drum-driving worm, taken on the line 10—10, Fig. 11, looking in the direction of the arrow;

Fig. 11 is a detail view showing the same mechanism;

Fig. 12 is a central, sectional view showing one of the record-strip carrying spools;

Fig. 13 is a central sectional view, taken on the line 13—13, Fig. 1, looking in the direction of the arrow;

Fig. 14 is a detail view, taken on the line 14—14 Fig. 15;

Fig. 15 is a detail view partly in section of the control rod shifting mechanism, showing the parts in operative profile-tracing position;

Fig. 16 is a view similar to Fig. 14 and taken on the line 16—16, Fig. 17, showing the same parts but in position assumed during the return of the profile tracer by the translating screw;

Fig. 17 is a view similar to Fig. 15 but showing the parts in the same position as in Fig. 16;

Fig. 18 is a top plan view of the parts shown in Figs. 16 and 17;

Fig. 19 is a longitudinal, central sectional view of the upper variable-speed friction gear; and

Fig. 20 is a similar sectional view of the lower variable-speed friction gear.

The device shown in the drawings, for the purpose of illustrating the invention, is designed to be carried upon any vehicle and to automatically record upon a record strip carried in the device a delineation of the profile of the road or surface over which the vehicle travels. The machine comprises a pendulum 1, Fig. 1, mounted to swing on the pivots 2 in a vertical plane parallel to the direction of travel of the vehicle upon which the device is carried, thus indicating the grade; and a record-carrying drum 3, Fig. 2, which is driven by suitable mechanism at a speed corresponding to the speed of the vehicle in which the device is mounted. All parts are mounted in a suitable rigid frame and may be inclosed in a casting, if desired. The delineation of the profile of the road is in operation traced upon the record strip 4, Fig. 13, carried by the drum, by a profile tracer 5 which is moved transversely of the record strip under the control of the grade-indicating pendulum 1. A pencil holder and pencil 6 form a part of the profile tracer. Profile plotting paper of usual type is used on the machine, and the gearing is designed to correspond with the particular paper to be used.

The mechanism for driving the record drum is shown most clearly in Figs. 1 and 3. Power is derived from the running gear of the vehicle (not shown) by means of a flexible shaft 8, such as ordinarily used to drive speedometers. Said flexible shaft drives a worm gear 9, Fig. 13, and worm 10 which, in turn, drives a worm wheel 11 rigidly mounted on a horizontal shaft 12 having at its 5 farther end a bevel gear 14 adapted to be meshed with a corresponding bevel gear 15 on the vertical principal driving shaft 16 of the device, which shaft is hereinafter termed the driving shaft. On the drive shaft is 10 slidably mounted a pair of rigidly-connected, reversing bevel gears 17, 18, Figs. 5, 3 and 4, a gear shifter 19 being connected to said pair of bevel gears to shift one or the other thereof into mesh with a bevel gear 20 upon 15 the end of a horizontal worm shaft 21 having at its farther end a worm 22 meshing with the worm wheel 23 upon the end of the record drum 3. The bevel gears of this train of gearing, as shown, are all miter gears, so that the record-driving worm 22 20 is driven at the same speed as the first worm wheel 11. It is occasionally desirable, however, to provide for driving the record drum at a faster speed in order that a larger scale 25 profile map may be obtained. Accordingly, adjacent the driven bevel gear 20 of the reversing mechanism is secured a second bevel gear 25, Fig. 3, of smaller diameter, as, for example, of one-half the size; and a gear 30 shifter 26 is adapted to shift either of the gears 20, 25 along the shaft to position for engagement with either of the reversing gears 17, 18. The reversing gears may then 35 be shifted by means of the gear shifter 19 40 to engage the driven gear. The gear shifter is operated by means of a hand wheel 28 with rack and pinion connection to shift either of the reversing gears 17, 18 into engagement with whichever of the gears 20, 45 25 is in position to be engaged thereby. Two record-carrying spools 30, 31 are rotatably mounted adjacent to and parallel to the record drum 3. These spools are removably mounted in the usual manner, as 50 shown in Fig. 12, in order to facilitate removal and replacement of the record strips. In operation, the record strip wound upon one of the spools, is passed over and around the record drum 3 and secured to the second 55 record spool. The spools and the record strip are driven, as shown in Fig. 13, by a tape 32 passing around the record drum and both spools. Such tape engages the surface of the record strip upon the drum and spools, 60 thereby maintaining the proper ratio of speed of the winding and unwinding spools. Guide wheels 33, 34 may be provided to insure accurate running of the tape. A tape tightener 35 is preferably provided, as shown 65 in Fig. 13, to maintain the tension of the

tape. This tape tightener, illustrated in detail in Figs. 6 and 7, comprises a transverse shaft 36 on which are mounted near the ends thereof flanged pulleys 39, 39 over which the aforesaid tape passes. The ends 70 of the shaft are mounted in bearings 40, which may be moved forwardly or rearwardly by means of the screws 41 to adjust the tension of said tapes.

The travel of the record strip under the 75 profile tracer is, when driven by the mechanism above described, proportional to the linear speed of the vehicle. When the vehicle is traveling upon a slope, the linear travel is greater than the horizontal distance traversed. This unless corrected, introduces an error in the profile map. Accordingly, it is desirable to correct the error there introduced.

In order to make such correction, a variable-speed gearing controlled by the grade-indicating pendulum is provided, so as to reduce the speed of motion transmitted to the record-strip drum in proportion to the grade on which the vehicle is traveling. 85 Such variable speed gearing consists of a tapered friction cone 44, Fig. 1, secured upon the horizontal shaft 12, and a second complementary friction cone 45 secured to a parallel shaft 46. Rotation is transmitted 90 from the driving cone to the complementary cone 45 by means of a friction gear 47 which is slidably mounted therebetween. The position of the said intermediate friction gear is controlled by arms 48, 49, Fig. 13, projecting vertically upward from the pendulum and engaging the sliding carriage 50 in which said friction wheel is mounted. The friction cones or drums are so proportioned that the speed transmitted through such gearing 95 will vary as the cosine of the angle of the grade. Accordingly, the record drum 3 will be driven at a speed corresponding to the horizontal traverse, instead of being driven at a speed corresponding to the linear speed 100 of the vehicle.

The parallel shaft 46 is adapted to drive the vertical drive shaft 16 through the miter gear 52 splined upon the end of the parallel shaft in position to engage a corresponding 115 gear 53 fast to the drive shaft 16. The gear 14 on the end of the horizontal shaft 12 is also splined to its shaft, and a gear shifter 54 is provided to control both gears, whereby either one or the other of the splined 120 gears may be moved into engagement with the corresponding gear on the drive shaft. The friction gearing may thus be interposed in the driving gearing or not as it is desired 125 to make correction for grade or to omit such correction.

In order to produce the profile as desired upon a record strip, it is necessary that the profile tracer 5 be driven along the record drum 3 in a direction transverse to the move- 130

ment of the record strip at a speed which will correspond to the grade up or down which the vehicle is traveling. In the construction shown, this is accomplished by 5 providing a variable-speed gearing between the drive shaft 16 which is driven constantly, as above described, and a grade screw 75 which is adapted to move the profile tracer 5 forward and back in a line 10 transverse to the direction of movement of the record strip.

This variable-speed gearing is under control of the pendulum grade indicator 1. This gearing comprises a bevel gear 57, 15 Fig. 1, secured to the upper end of the vertical drive shaft 16 meshing with a corresponding bevel gear 58 secured to the end of a horizontal splined shaft 59 on which is splined a bevel gear 60. A carriage 61 is 20 mounted in ways in the frame of the machine to move parallel to the horizontal splined shaft 59, and to this carriage is secured a bracket in which is rotatably mounted the splined bevel gear 60, and a short 25 horizontal shaft having at one end a bevel gear 63 meshing with the splined bevel gear 60 and having at its outer end a friction disk 65. The friction disk is thus mounted in the carriage in a manner to be moved laterally 30 while being constantly driven from the splined shaft. Parallel to the face of the disk the shaft 66, Figs. 9 and 13, is rotatably mounted and carries adjacent its inner end a friction wheel 67, and at its outer end a 35 bevel gear 68. The friction wheel 67 bears against the face of the friction disk. The face of the disk is constantly in contact with the friction wheel 67, and as the carriage reaches the central position or moves to one 40 side or the other, the center of the disk or one side or the other thereof is in contact with the friction wheel.

The center of the disk 65 is made smooth to prevent useless wear upon the driven 45 friction wheel 67 when the disk is centrally positioned. The remainder of the disk may be prepared as desired to provide a driving surface.

The position of the carriage 61, Fig. 2, 50 and, therefore, of the friction disk 65, is controlled by the grade-indicating pendulum 1. For this purpose, the vertically extending arm 49 rigidly connected to the pendulum engages the carriage 61 and there- 55 by as it swings with the pendulum moves the carriage forward and back, thus holding the carriage at a position always corresponding to the grade. The velocity at which the friction gear 67 is driven and the 60 direction in which it is driven thus correspond to the amount and direction of grade. The carriage, friction disk and associated parts are preferably of aluminum to reduce weight.

65 In order to maintain the disk 65 in true

alignment and insure accurate running and operation thereof, anti-friction devices 70 are provided which are positioned in a plane to engage the face of the disk. As the disk is moved forwardly and backwardly, it is 70 always in engagement with a larger or smaller number of these anti-friction devices. Such devices are conveniently shown and may be of any desired type. The driven shaft 66, through the co-operating bevel 75 gears 68 and 71, drives the short vertical shaft 72, and the bevel gears 73 and 74 drives a horizontal grade screw 75. This screw is preferably of slow pitch threaded substantially from end to end and lies parallel to the record drum 3. The profile tracer 5 is slidably and pivotally mounted upon the transverse supporting rod 77, Fig. 2. The rear end of the tracer arm is provided with a nut segment 78, Fig. 8, which engages the 80 screw 75 upon its under side when the pencil 6 is in engagement with the record strip. The pencil is thus moved longitudinally of the record drum 3 and transversely of the 85 line of movement of the record strip by the 90 gearing above described at a speed which corresponds with the steepness of the grade on which the vehicle is traveling, and the movement to one side or the other corresponds to the up or down grade. Furthermore, 95 the position of the pencil always records a position which corresponds to the elevation, from a given base line for which the device is adjusted. The angle of the line always corresponds to the slope on which 100 the vehicle is traveling. Whether such angle is exact or is exaggerated will depend upon the screw used and the proportion of parts and ratios of the gearing.

It sometimes occurs that when the road 105 being mapped includes considerable differences of elevation, the width of the record strip is insufficient for recording the complete profile. In order to overcome the difficulties thus involved, there is provided 110 mechanism for automatically moving the profile tracer 5 from one side to the other side of the record strip when the movement is such that otherwise it would pass beyond the limit of the width of the strip. This 115 mechanism is shown most clearly in Figs. 2, 8, and 9. A translating screw 80 of relatively high pitch is positioned parallel to the grade screw 75 and is driven therefrom by means of gears 81 and 82 at a consider- 120 ably greater speed than the grade screw. The tracer arm 5 is provided with a corre- 125 sponding nut segment 83 which, when the arm is rocked to the position shown in Fig. 8, engages the translating screw, and rotation of the screw, therefore, moves the arm transversely of the device upon its supporting rod 77. Because of the greater speed and pitch of the translating screw, the tracer arm is carried from side to side with such 130

rapidity that a relatively short section of the road remains untraced. Such section may be traced manually.

Automatically-operating mechanism is provided for shifting the tracer arm from position of engagement with the grade screw 75 to position for engagement with the translating screw 80, and for shifting the same back to operative position, again enabling the grade screw, when the tracer has been shifted to the opposite side of the record strip. The automatic shifting mechanism is shown in detail in Figs. 13 to 18. As shown, the shifting mechanism comprises a control rod 85 which extends transversely of the device and parallel to the tracer supporting rod 77, such rod being slidably engaged by the tracer arm. The control rod is provided with adjustable collars or stops 87, 87, Fig. 2, in position to be engaged by the tracer arm as the tracer approaches the end of the travel to automatically set in action the shifting mechanism. The rod passes at each end through a guide and supporting plate 88, Figs. 14 to 17, having two holes 89, 90 positioned to hold the rod in the positions to engage the tracer arm 5 with the grade screw and translating screw, the holes being of the size of a stop collar 91 secured to the rod and being connected by a slot of a width to permit passage therethrough of the rod 85. Springs 92, 92 spaced from the guide plate 88 and having slots through which the rod extends, engage opposite sides of the collar and tend to hold the same in central longitudinal position and in one of the retaining holes 89, 90 of the guide. At each end of the rod a plate 921 is secured having a vertical slot 93 with central lateral extensions 94, 94, in which slot operates a spring 95. The plate is double to extend on opposite sides of a bracket 96 which holds the plate upright. The spring projects from a pivoted block 97, Fig. 3, which is oscillated by an eccentric pin 98 projecting from the end of the translating screw shaft. The eccentric thus causes the spring to move up and down, and when the rod is moved laterally, as to the position shown in dotted lines in Fig. 15, the spring engages one of the lateral extensions of the slot and tends to raise or lower the rod. As the tracer arm approaches one of the extreme positions it engages the dog or carrier 87 carried on each end of the shaft 85 and shifts the entire shaft 85 longitudinally, that is transversely with respect to the record carrier, frame, etc., against the resilient opposition of the plate springs 92 which are engaged by a second collar 91 on each end of the shaft 85. This transverse movement of the shaft 85 moves these second collars 91 out of vertical alignment with the slot, connecting the openings 89 and 90 formed in

the plate 88, and as this slot is of sufficient width to permit passage therethrough of the shaft 85 but to prevent passage of the collar 91 when the collar has been moved out of alignment therewith, the pin 95 which is being substantially reciprocated engages the plate 921 and shifts the shaft 85 vertically upward. This vertical movement of the shaft 85 swings the tracer arm about its supporting shaft 77 so as to disengage the tracer arm from the grade screw 75 and engage it with the translating screw 80, or to disengage it from the translating screw 80 and engage it with the grading screw 75, as the case may be, it being understood that when the shaft 85 is shifted vertically upward it disengages the tracer arm from the grade screw and engages it with the translating screw and that when shaft 85 is shifted vertically downward it disengages the tracer arm from the translating screw and engages it with the grade screw. Such shifting of the profile tracer is, of course, the equivalent of shifting the record strip, and the delineation traced will be with respect to a different base line. The rod 85 may be counterbalanced or yieldably supported as by springs 99, if desired.

It will be understood upon inspection of the device that the transfer of the profile tracer from one side to the other under the action of the translating screw is necessarily accomplished while the vehicle is traveling over a certain easily determined difference in elevation. Accordingly, since this is constant, the dogs or collars 87, 87 may be so adjusted on the control rod that allowance is made for such inoperative movement; and when such allowance is made, the base lines of the profile traced before and after will have a certain desired relation to each other; for example, if profile paper ten inches in width be used, the difference between the two base lines of the two profiles traced may be ten inches, if the adjustment is properly made.

It is frequently desirable to rotate the profile drum, or record-strip drum, by hand, as when introducing or removing a record strip. To facilitate such movement, means are provided for disengaging the worm from the ends of the drum. As shown in Fig. 10, the worm shaft is mounted in a slideable journal 100 which may be moved out of and into position for engaging the worm with the worm wheel by means of a screw shaft 101 threaded into the journal block and secured against longitudinal movement in the frame of the machine, as indicated at 102. The hand wheel 103, Fig. 2, on the end of the shaft facilitates operation thereof. A suitable counter 104 may be attached at any convenient point in the gear, as, for example, at the end of the drum, in order to indicate the horizontal distance traversed; and, if de-

sired, an elevation meter 105 may also be connected at any suitable point to the profile-tracer operating mechanism in order to indicate the total change in grade. Such 5 meter may be provided with three dials, one of which indicates the total ascent, another which indicates the total descent, and the third of which may indicate the change of grade, that is, the difference.

10 It is desirable to provide means to lock the pendulum against swinging motion when the machine is not in operation but is being carried. Accordingly, I provide a locking bolt 108, Fig. 3, which may be inserted 15 through a hole in the frame and into a recess in the pendulum. Anti-friction rollers 109 are provided in the frame.

It is understood that the gearing hereinbefore described may be designed with regard to the particular requirements as to range of grade to be recorded and as to accuracy of results required. Satisfactory 20 results may be obtained for recording grades of twenty-five per cent. or less if, in the 25 machine especially illustrated in the drawing, the variable-speed friction gearing which modifies the speed of the drive shaft in accordance with the grade traversed, is made substantially as follows: the friction gear 30 44, one inch in diameter at its center and .976 inch in diameter at each end; the curve of an element of the surface being of a radius of 162 inches; the gear 45 one inch in diameter at its center, 1.024 inches in diameter at each end, the curve of an element 35 of the surface being of a radius of 162 inches; and the distance from the pivot 2 of the pendulum to the center of the intermediate friction gear 47, six and one-quarter 40 inches. The distance from the pivot 2 of the pendulum to the center of the grade disk 45 may be twelve and one-half inches, and the grade disk may be of a diameter of six and one-quarter inches. The grade screw and gearing connecting the same is designed accordingly to suit the profile paper used.

It will be understood that while I have 50 illustrated an operative embodiment of the invention, changes may be made without departing from the spirit of the invention as set forth.

Having thus described my invention, I claim as new and desire to secure by Letters Patent:

55 1. In a profile delineating device for use on a traveling vehicle, a drive shaft; means for driving said drive shaft at a speed corresponding to the horizontal traverse of the vehicle; record-strip supporting means; selective-speed gearing driven by the drive 60 shaft and coöperating with the record-strip supporting means for feeding a record strip at any one of a plurality of speeds to vary the scale of the profile; a profile tracer mounted to engage and traverse the record

strip; and driving means driven by the drive shaft to move said tracer transversely of the record strip at a speed corresponding to the grade over which the vehicle is traveling.

2. In a profile delineating device for use on a traveling vehicle, a drive shaft; means for driving said drive shaft at a speed corresponding to the horizontal traverse of the vehicle; record-strip supporting means; selective-speed gearing driven by the drive shaft and coöperating with the record-strip supporting means for feeding a record strip at any one of a plurality of speeds to vary the scale of the profile; a profile tracer movable transversely of the record strip; a grade indicating device; and variable speed gearing driven by the drive shaft and controlled by the grade indicating device to move the profile tracer transversely at a speed corresponding to the grade over which the vehicle is traveling.

3. In a profile delineating device for use on a traveling vehicle, a drive shaft; means for driving said drive shaft at a speed corresponding to the horizontal traverse of the vehicle; record-strip supporting means; single-speed gearing driven by the drive shaft and coöperating with the record-strip supporting means for feeding a record strip; a profile tracer movable transversely of the record strip; a grade-indicating device; variable speed gearing driven by the drive shaft and controlled by the grade indicating device to move the profile tracer transversely in a direction and at a speed corresponding to the grade over which the vehicle is traveling; and means for moving the profile tracer relatively quickly from one extreme transverse position to the opposite 100 extreme transverse position.

4. In a profile delineating device for use on a traveling vehicle, a drive shaft; means for driving said drive shaft at a speed corresponding to the horizontal traverse of the vehicle; record-strip supporting means; single-speed gearing driven by the drive shaft and coöperating with the record-strip supporting means for feeding a record strip; a profile tracer movable transversely of the record strip; a grade indicating device; variable speed gearing driven by the drive shaft and controlled by the grade indicating device to move the profile tracer transversely in a direction and at a speed corresponding to the grade over which the vehicle is traveling; and auxiliary means co-operating with the variable-speed gearing and automatically set in operation as the profile tracer approaches one extreme of its travel to move said tracer to the opposite extreme of its travel.

5. In a profile delineating device for use on a traveling vehicle; a frame; a drive shaft carried by said frame, means for driv-

- ing said drive shaft at a speed corresponding to the travel of the vehicle, carried by said frame; record-strip supporting means carried by said frame; gearing driven by 5 the drive shaft and coöperating with the record-strip supporting means for feeding a record strip, said gearing being carried by said frame; a profile tracer carried by the frame and slidably mounted for movement transversely of the record strip; and means for driving said profile tracer including a friction wheel carried by the frame; ways carried by the frame and extending transversely of the friction wheel; 10 a carriage mounted in said ways, a friction disk mounted upon said carriage engageable with said friction wheels; and a grade-control pendulum suspended from said frame and actuating said carriage whereby 15 to move said friction wheel relative to said friction disk and vary the speed of the profile tracer correspondingly with the grade over which the vehicle is traveling.
6. In a device of the character described, 20 a movable record strip, a profile tracer mounted to move transversely of the record strip and to engage the same; a screw of relatively low pitch with which said profile tracer is engageable to be moved thereby; a second screw parallel thereto and of relatively high pitch with which said profile tracer is engageable alternatively with said low-pitch screw; a grade-indicating device; 25 variable-speed gearing controlled by the grade-indicating device to drive said low-pitch screw at a relatively low speed and said high-pitch screw at a relatively high speed; and means for holding said profile tracer in coöperative engagement with said 30 screws alternatively.
7. In a device of the character described, 35 a movable record strip, a profile tracer mounted to move transversely of the record strip and to engage the same; a screw of relatively low pitch with which said profile tracer is engageable to be moved thereby; a second screw parallel thereto and of relatively high pitch with which said profile tracer is engageable alternatively with said 40 low-pitch screw; a grade-indicating device; 45 variable-speed gearing controlled by the grade-indicating device to drive said low-pitch screw at a relatively low speed and said high pitch screw at a relatively high speed; and means for holding said profile tracer in coöperative engagement with said 50 screws alternatively, comprising means to automatically shift the profile tracer from engagement with one screw to engagement 55 with the other screw as the profile tracer approaches either extreme position of travel when driven by either screw.
8. Stylus shifting means for use on a profile delineating device including a stylus, a 60 stationary supporting shaft on which said

stylus is mounted for sliding and swinging movement, a vertically and longitudinally movable shaft associated with said stylus, and means adapted to shift said vertically movable shaft to reverse the motion of said 70 stylus when it approaches either extreme position of travel.

9. Stylus shifting means for use on a profile delineating device including a stylus, a stationary supporting shaft on which said 75 stylus is mounted for sliding and swinging movement, and a movable shaft associated with said stylus to reverse the motion of said stylus when it approaches either extreme 80 position of travel.

10. In a profile delineating device for use on a traveling vehicle; a frame; a drive shaft carried by said frame, means for driving said drive shaft at a speed corresponding to the travel of the vehicle, carried by 85 said frame; record-strip supporting means carried by said frame; gearing driven by the drive shaft and coöperating with the record-strip supporting means for feeding a record strip, said gearing being carried 90 by said frame; a profile tracer carried by the frame and slidably mounted for movement transversely of the record strip; means for driving said profile tracer including a friction wheel carried by said frame, ways carried by said frame and extending transversely of said friction wheel, a carriage mounted in said ways; a friction disk journaled on said carriage and engaged 95 with said friction wheel, a jack shaft carried by said frame and having its axis parallel to the line of motion of said carriage and arranged adjacent said carriage, gearing for driving said friction disk from 100 said jack shaft carried by said carriage and including a pinion slidably keyed on said jack shaft and a grade-control pendulum suspended from said frame and actuating said carriage whereby to move said friction wheel relative to said friction disk and vary 105 the speed of the profile tracer correspondingly with the grade over which the vehicle is traveling.

11. Stylus shifting means for use on a profile delineating device including a stylus, a stationary supporting shaft on which said stylus is mounted for sliding and swinging movement and a vertically movable shaft associated with said stylus thereby to effect reversal of motion of the stylus when it 115 approaches either extreme position of travel.

12. Stylus shifting means for use on a profile delineating device including a stylus, a supporting shaft upon which said stylus is mounted; a vertically and longitudinally 120 movable shaft associated with said stylus; a collar carried on each end of said last mentioned shaft adapted to be engaged by the stylus to move this shaft longitudinally, and means operative to move said last men- 125 130

tioned shaft vertically when it has been moved longitudinally by said stylus thereby to effect reversal of motion of the stylus when it approaches either extreme position 5 of travel.

18. Stylus shifting means for use on a profile delineating device including a stylus, a supporting shaft upon which said stylus is mounted, a vertically and longitudinally 10 movable shaft associated with said stylus, a collar carried on said last mentioned shaft adjacent the point of extreme travel of the stylus and adapted to be engaged by the stylus to move this shaft longitudinally; 15 means resiliently resisting longitudinal movement of said shaft; means preventing vertical movement of the shaft, except when it has been displaced longitudinally; and means operative to move said last named 20 shaft vertically when it has been displaced longitudinally thereby to effect reversal motion of the stylus when it approaches either extreme position of travel.

14. Stylus shifting means for use on a 25 profile delineating device including a stylus,

a supporting shaft upon which said stylus is mounted, a vertically and longitudinally movable shaft associated with said stylus, a collar carried on said last mentioned shaft adjacent the point of extreme travel of the 30 stylus and adapted to be engaged by the stylus to move this shaft longitudinally; means preventing vertical movement of the shaft, except when it has been displaced longitudinally; and means operative to move 35 said last named shaft vertically when it has been displaced longitudinally thereby to effect reversal motion of the stylus when it approaches either extreme position of travel.

15. Stylus shifting means for use on a 40 profile delineating device including a stylus; a grade screw associated with said stylus; a translating screw associated with said stylus; a stationary supporting shaft on which said stylus is mounted for sliding and swinging 45 movement; and a movable shaft associated with said stylus to reverse the motion of said stylus when it approaches either extreme position of travel.
